EDWARD H. GOHL, OF AUBURN, NEW YORK.

DECORATIVE STREET-POST.

1,262,776.

Specification of Letters Patent. Patented Apr. 16, 1918.

Application filed November 27, 1916. Serial No. 133,661.

To all whom it may concern:

Be it known that I, EDWARD H. GOHL, a citizen of the United States of America, and resident of Auburn, in the county of 5 Cayuga, in the State of New York, have invented new and useful Improvements in Decorative Street-Posts, of which the following, taken in connection with the accompanying drawings, is a full, clear, and exact 10 description.

This invention relates to certain improvements in flag-holders for street lamp-posts or poles, and involves some of the features of my Patent No. 1,223,487, issued April 24, 15 1917, but is distinguished therefrom in that it is applied circumferentially around the top of the pole instead of to the arms thereof.

The main object is to provide permanently located street posts or poles with simple means whereby a considerable number of flags may be conveniently and systematically installed in clusters upon such post or pole for decorative purposes and as easily 20 25 30 35 40 conveniently removed when desired, without disturbing the flag-receiving elements from the pole so that the same elements may be reused for receiving the same or other decorative flags without further labor or expense than the mere insertion of the flag staffs therein, thus providing decorative schemes through the various streets which are not only pleasing from an artistic point of view, but also avoids the unsightly appearance and large expense of promiscuous decorations upon buildings and wires or ropes across the street, and reduces the danger to pedestrians from falling decorations, resulting from improper secure- 45 ment.

Other objects relating to specific parts of the device will be brought out in the following description.

In the drawings—

45 Figure 1 is a top plan of my improved flag-holder as operatively mounted on a post which is shown in section.

Fig. 2 is a side elevation of the same flag-holder and a portion of the street post.

50 Fig. 3 is a horizontal sectional view taken on line 3—3, Fig. 2.

As illustrative of one use of my invention, I have shown a portion of a cast metal post —1— and a plurality of flag-receiving 55 sections or wings —2— clustered systematically around and upon the periphery of

the main body of the post, and having staff-receiving sockets 3 at an angle thereto so as to incline outwardly and upwardly in different radial planes uniform distances apart, 60 said sections being also provided with substantially horizontal sockets or apertures —4— for receiving flag-staffs —5— and —5—, respectively, as shown more clearly in Fig. 1, and by dotted lines in Fig. 2. 65

The sockets —3— extend upwardly and outwardly from the main body of the post to the upper ends of the wings —2— and at substantially the same angle to the axis of said post so as to allow the lower ends of 70 the flag staffs to be wedged tightly between the outer walls of the wings and main body of the post, while the upper portions of the flag staffs carrying the flags will be caused to stand out some distance from the post 75 to allow said flags to wave or float freely without becoming entangled with each other or with the post.

Each socket 3 is provided with three bearings for the flag staff arranged in spaced 80 relation one above the other and consisting of lower and upper bearings —6— and —7— forming the outer walls of the socket, and an intermediate bearing —8— registering with the space between the bearings —6— 85 and —7— and forming the inner wall of the socket, the distance from the bearing —8— directly across the socket to a direct line drawn between the bearings —6— and —7— being slightly less than the diameter of the 90 flag staff so as to cause the portion of the staff which engages the bearing —8— to bow outwardly slightly in the intervening space between the bearings —6— and —7— for the purpose of frictionally holding the 95 flag staffs in operative position with greater security, thereby avoiding the necessity of using any other fastening means and permitting the flag staffs to be readily inserted into or removed from the sockets at will. 100

The sockets or apertures —4— extend transversely through the wings —2— between the lengthwise sockets —3— and main body of the post, one end the same of each of the sockets —4— being slightly 105 higher than the opposite end, as shown more clearly in Fig. 2, to cause the flag staffs which they are adapted to receive to lie in a slightly inclined plane from a horizontal position sufficient to allow the intermediate 110 portion of each staff to overlie the low end of the next adjacent staff in the manner

shown in Fig. 1, thus giving the flag-supporting ends at a slight tilt upwardly away from the post.

The sections 2 are connected to each other 5 by hinge bolts or pivots —9— to form a sectional band or collar encircling the post and closely fitted thereto so as to be self-retaining by friction therewith, it being understood that these posts are usually tapered 10 upwardly and that the sections of the band may be readily assembled upon a relatively small portion of the post and then slipped downwardly until wedged tightly thereon ready for use.

15 These wings —2— are preferably cast in the same mold and are, therefore, of the same size and form and are readily interchangeable, each wing being provided with laterally projecting arms —10— having 20 apertured lugs —11— and —11'— at their ends for receiving the pivotal bolts —9— which are removable to allow the use of any number of the wings according to the size of the post.

25 It is, therefore, evident that instead of using four of these wings, as shown in the drawings, for a certain size post, one of them may be removed and the ends of adjacent wings reconnected by one of the pivotal bolts —9— for use on a smaller post, or if the wings are to be used with a larger post, any one of the pivotal pins —9— may 30 be withdrawn and one or more additional sections inserted, thus providing a wide 35 range of adjustment of the device for differ-

ent sizes of posts, an indication of which is shown by dotted lines in Fig. 3, in which one of the sections is removed and the adjacent sections reconnected for a post of smaller size.

The operation of my invention will now be readily understood upon reference to the foregoing description and accompanying drawings, but it is evident that the design of the wings may be materially changed 45 without departing from the spirit of my invention and, therefore, I do not wish to limit myself to the construction shown and described.

What I claim is:

1. In combination with a street post, a plurality of wings clustered about the periphery of the post and provided with upwardly and outwardly inclined sockets for receiving a corresponding number of flag staffs, said wings being provided with openings extending transversely of the sockets for receiving additional flag staffs.

2. In combination with a street post, a collar therefor composed of similar sections arranged edge to edge circumferentially and provided with sockets for receiving flag staffs, and devices for clamping the adjacent edges of the sections together.

In witness whereof I have hereunto set my hand this 21st day of November, 1916.

EDWARD H. GOHL.
